INVENTOR

J. H. E. E.

United States Patent Office.

GEORGE JONES, OF SAUGERTIES, NEW YORK.

Design No. 2,598, dated March 19, 1867.

DESIGN FOR COFFEE AND TEA-POT TOPS.

The Schedule referred to in these Letters Patent and making part of the same.

TO ALL WHOM IT MAY CONCERN:

Be it known that I, GEORGE JONES, of Saugerties, in the county of Ulster, and State of New York, have invented a new Design for Coffee and Tea-Pot Tops; and I do hereby declare the following, when taken in connection with the accompanying drawings, and the letters of reference marked thereon, to be a full, clear, and exact description of the same, and which said drawings constitute part of this specification, and represent, in—

Figure 1, a side view; and in

Figure 2 the top detached from the cover.

This invention relates to a design for the top (as it is commonly called) of tea or coffee-pots, but may be better distinguished in this description by calling it the ornament upon the cover.

The design consists in a ball or sphere, A, mounted upon a cavetto base, B, formed with a fillet between the base and the sphere; also a fillet which forms a shoulder upon the cover, as seen in the drawings, which said base is secured to the cover C; and I claim as my invention—

The design herein illustrated and described for the top or ornament for tea or coffee-pot covers.

GEORGE JONES.
